UNITED STATES PATENT OFFICE.

ROY V. COLLINS, OF NEWTONVILLE, MASSACHUSETTS, ASSIGNOR TO COLLINS SWITCH & SIGNAL COMPANY, OF NEW YORK, N. Y., A CORPORATION OF NEW YORK.

AUTOMATIC ELECTRICALLY-CONTROLLED TRACK SWITCH.

Application filed April 3, 1923. Serial No. 629,693.

To all whom it may concern:

Be it known that I, Roy V. Collins, a citizen of the United States, and resident of Newtonville, county of Middlesex, State of Massachusetts, have invented an Improvement in Automatic Electrically-Controlled Track Switches, of which the following description, in connection with the accompanying drawing, is a specification, like characters on the drawing representing like parts.

This invention relates to a track switch for use in electric car lines and particularly to an electrically-actuated switch which is automatically controlled by the movement of the trolley past a predetermined point. These electrically-actuated switch devices usually include a switch-throwing magnet or solenoid by which the switch is thrown, a suitable contactor associated with the trolley wire and adapted to be engaged by the trolley wheel and means whereby the engagement of the contactor by the trolley wheel will operate to close the circuit of the switch-throwing magnet.

One of the objects of my present invention is to provide a novel construction by which when the circuit for the switch-throwing magnet has been closed by the engagement of the trolley wheel with the contactor, said circuit will remain closed for a predetermined length of time and then will be automatically opened regardless of the length of time with which the trolley wheel engages the contactor.

The current which is necessary to operate the switch-throwing magnet is a relatively heavy current and an advantage of this construction which involves a timing element for timing the length of time which said switch-throwing circuit shall be closed is that it ensures that said circuit will always be closed long enough to properly actuate the switch-throwing magnet and then will be automatically opened without regard to

the position of the trolley wheel with relation to the contactor. The automatic opening of the circuit after it has been closed for a sufficient length of time to actuate the switch prevents any possibility of overheating the switch-throwing magnet due to the heavy current remaining thereon unnecessarily after the magnet has performed its function.

The circuit of the switch-throwing magnet

is closed by a timing relay which has the timing element associated therewith and the circuit for the timing relay is arranged so that it will be closed when the trolley wheel engages the contactor. The closing of the timing relay circuit for an instant only is sufficient to energize said relay and to close the circuit for the switch-throwing magnet, and the timing element associated with the timing relay maintains the circuit for the switch-throwing magnet closed for the appropriate length of time regardless of the length of time that the circuit for the timing relay is closed and, therefore, even if the trolley car should stop with its trolley in engagement with the contactor yet the circuit for the switch-throwing magnet would be opened after said magnet had performed its function.

My invention also comprehends a construction by which the switch-throwing magnet is prevented from being operated a second time until the car which has operated it the first time has passed beyond the switch, this construction making it impossible for a car which is following the car which has thrown the switch from disarranging the switch until said car has passed the switch.

In order to give an understanding of the invention I have illustrated in the drawings a selected embodiment thereof which will now be described after which the novel features will be pointed out in the appended claims.

Fig. 1 is a view in the nature of a wiring diagram illustrating the wiring connection of my improved apparatus;

Fig. 2 is a view showing the parts of the apparatus enclosed in a casing, the cover and the casing being removed to better illustrate the device;

Figs. 3 and 4 are detail views of the timing element showing the parts in different position;

Fig. 5 is a view of the contactor;

Fig. 6 is an end view of the contactor;

Fig. 7 is a view of the unlocking contactor;

Fig. 8 is a section on the line 8—8, Fig. 5;

Fig. 9 is a fragmentary plan view of the unlocking contactor shown in Fig. 7.

In Fig. 1 of the drawings 1 indicates the trolley wire and 2 indicates the track switch which is actuated by the two solenoids or

magnets 3 and 4, the solenoid 3 operating to move the switch 2 in one direction and the solenoids 4 operating to move it in the opposite direction. The circuits for the magnets 3 and 4, which will be more fully hereinafter described, are closed by a timing relay indicated at 6 and the circuit for this relay is closed thereby to make it operative by the trolley wheel 7 of a trolley car 10 engaging a contactor, shown generally at 8, which is associated with the trolley wire 1. The contactor herein shown is in the form of two shoes or contact strips 9 that are situated either side of the trolley wire 1 and 15 are so arranged that as the trolley wheel passes the contactor the flanges of the trolley wheel will engage the contacts 9 as shown in Fig. 6 and in doing so will be withdrawn from engagement with the trolley wire 1. 20 The trolley wheel, therefore, bridges the contacts 9 while in engagement with the contactor.

The two shoes 9 are shown as suspended from two strips 10 of wood or other insulating material, said strips in turn being supported by the trolley ears 11. These shoes or contacts 9 are shown as having extensions 99 rising therefrom, each extension having on its upper end a seat 98 resting against 25 the under side of the two wooden strips 10. These extensions 99 are secured to the wooden strips by bolts 97 which extend between the wooden strips and through clamping plates 96 which overlie said wooden strips. The contacts or shoes 9 are thus insulated from the trolley wire and from each other. These contact strips are in the circuit of the timing relay 6, said circuit being normally open between said contacts but being closed when the trolley wheel 7 bridges the contacts as shown in Fig. 6. This circuit of the timing relay 6 is herein illustrated as follows. It consists of a wire connection 12 connected to the trolley wire 1 at 30 13 and leading to one blade 14 of a three-pole switch 15, wire connection 16 leading to a selective relay 17, which will be herein-after described, and which operates to select which of the two switch-throwing magnets 3 and 4 shall be operated, a wire connection 18 leading from the magnet 17 to a binding post 19, wire connection 20 leading to one of the contact strips 9 through the blade 21 of the three-pole switch 15, a wire connection 22 leading from the other contact strip 9 through the third blade 23 of the three-pole switch 15, wire connection 24 leading from said blade 23 to the timing relay 6, (said wire connection 24 being shown as having a fuse 25 therein) and wire connection 26 which leads to the ground at 27 and is provided with a suitable resistance 28 therein.

From the above it will be seen that when the three-pole switch 15 is closed the circuit of the relay 6 will be normally open between

the two contact strips 9 but when the trolley wheel 7 engages said strips 9 and bridges the latter, as shown in Fig. 6, the above-described circuit through the timing relay 6 will be completed and the latter will be 70 energized. When the trolley wheel engages the contact strips 9 it is separated from the trolley wire 1 so that no current will pass directly from the trolley wire to the trolley wheel and, therefore, the current can only 75 take the path above outlined which includes the timing relay 6.

As stated above the energizing of the timing relay 6 by the engagement of the trolley wheel with the contactor 8 serves to close the circuit through one of the switch-throwing solenoids 3 or 4. This relay 6 is provided with an armature 29 which is pivotally mounted at 30. A contact arm 31 is also pivoted at 30 co-axially with the armature 29 and carries a bridging contact 32 that is adapted to bridge two contacts 33, 34 in the circuit of the switch-throwing magnet. The armature of the relay is normally held in its raised position shown in Fig. 1, with the bridging contact 32 separated from the contacts 33, 34 but when the timing relay 6 is energized the armature 29 is attracted thereby swinging the bridging contact 32 into engagement with the contacts 33, 34 and closing the circuit of the switch-throwing magnet. 90

The timing relay has associated therewith timing means for determining the length of time that the bridging contact 32 will remain in engagement with the contacts 33, 34, said timing mechanism being constructed so that the contacts 33 and 34 will be opened after a predetermined length of time. This timing mechanism will be hereinafter described. 100

The circuit for the switch-throwing magnet, which is closed at the contacts 33, 34, is connected to the circuit for the timing relay at the binding post 19. The complete circuit for the switch-throwing magnet, therefore, comprises the wire connection 12, switch blade 14, wire connection 16, the windings to the selective relay 17, wire connection 18 to the binding post 19, 110 wire connection 35 leading from the binding post 19 to the stick relay 36, which will be herein-after described, (said wire connection 35 having the fuse 37) windings of stick relay 36, wire connection 38 leading to the contact 34, wire connection 39 leading from the contact 33 to the armature 40 of the selective relay 17 and either contact 41 and wire connection 42 leading to the switch-throwing solenoid 4 or contact 43 and wire connection 44 leading to switch-throwing solenoid 3, and from one or the other of said switch-throwing solenoids 115 to the ground at 45. The armature 40 of the selective relay 17 is adapted to engage 120

either of the contacts 41 or 43 and the position of this armature is determined by the selective relay 17. When the selective relay 17 is not operative then the armature 40 engages the contact 41 and the switch-throwing solenoid 4 is in the circuit while when the selective relay 17 is operative the armature 40 is raised into engagement with the contact 43 so that the switch-throwing solenoid 3 is in the circuit.

Means are provided, which will be hereinafter described, by which the motorman on the electric car can control the operation of the selective relay and thereby determine which one of the switch-throwing solenoids 3 or 4 will be energized.

The engagement of the trolley wheel with the contactor 8, therefore, energizes the timing relay 6 and causes the latter to operate to close the circuit through one or the other of the switch-throwing solenoids by means of the bridging contact 32 engaging the contacts 33, 34.

The timing relay 6, the selective relay 17, the stick relay 36, fuses 25, 37 and the resistance 28 are all preferably mounted in a suitable housing 46, as illustrated in Fig. 2. The timing mechanism which is associated with the timing relay comprises a lever 47 pivotally mounted co-axially with the armature 29 but independently thereof, said lever carrying at its opposite ends two weights 48, 49, the weight 49 being slightly heavier than the weight 48 so that it will overbalance the latter. The arm 31 carrying the bridging contact 32 is also pivotally mounted co-axially with the armature but independently thereof and means are provided whereby normally the arm 31 is latched to the armature so that when the armature is drawn downwardly the arm 31 will be swung forwardly to close the contacts 33, 34. This latching means comprises a latch 50 which is pivotally mounted at 51 on an extension 52 of the armature 29, said latch normally engaging a lug or projection 53 formed on the arm 31 so that when the armature 24 is swung downwardly into the position shown in Fig. 3, the latch 50 will operate to swing the arm 31 forwardly.

The latch is constructed so that it is automatically released from the lug 53 when the arm 31 has been carried into a position to bridge the contacts 33, 34 and this is accomplished by providing the latch with a tail 54 which engages an adjustable stop screw 55 when the armature is in its lowered position shown in Fig. 3. The engagement of the tail 54 with the stop screw rocks the latch thereby disengaging it from the lug 53 as shown in Fig. 3.

The weighted lever 47 with its weights 48, 49 constitute the timing element which governs the time during which the circuit

of the switch-throwing magnet will be closed at the contacts 33, 34. This lever 47 is provided with a lug 56 which normally engages the projection 53 on the arm 31, said lug being held in engagement with the projection 70 because the weight 49 is greater than the weight 48. Therefore, when the armature 24 is drawn downwardly, as shown in Fig. 3, the movement of the arm 31 is transmitted to the lever 47 through the lug 56, 75 so that during the downward movement of the armature 24, said armature and the arm 31 and lever 47 turn as a unit about the pivotal point 30. This downward movement of the armature will, of course, be a rapid one, and since the lever 47 is free to turn on the pivot 30 the momentum of the lever and the weights will cause said lever to continue turning after the armature has reached the limit of its downward movement as shown 80 in Fig. 3 so that the lug 56 on the lever 47 will be separated from the projection 53. The lever 47 will continue its forward turning movement after the contacts 33, 34 are closed until the preponderance of the weight 90 49 over the weight 48 overcomes the momentum of the weighted lever and begins to restore the lever to its normal position. As soon as the momentum of the lever 47 has thus been overcome the heavier weight 95 49 begins to turn the lever 47 back to its normal position and during this return movement the lug 56 will engage the projection 53 on the arm 31 and carry said arm backwardly 100 into the position shown in Fig. 4, this being permitted because of the fact that the latch 50 is released from the projection 53 as shown in Fig. 3. It might be stated that when the arm 31 is in a position in which the contact 32 is bridging the contacts 33, 34, said arm will be held by gravity in its position until it is restored to its initial position by the return weighted lever 47.

The length of time, therefore, which the circuit of the switch-throwing magnet will be closed depends on the time required for the greater weight 49 to absorb the energy of momentum of the differential weighted lever 47 and return said lever into a position 110 to engage the projection 53 on the arm 31. The parts are so constructed that the time thus required is sufficient for the switch-throwing magnet to accomplish its function.

The construction of this timing mechanism is such that the circuit of the switch-throwing magnet will be opened automatically after the predetermined time regardless of whether the timing relay 6 continues to be energized or not, for as soon as the armature has been drawn down to the solenoid as shown in Fig. 3 the arm 31 will be unlatched from the armature and it is thus free to return to its normal position, even though the armature remains in the lowered position.

The advantage of this construction is that it obviates any danger of injury to either of the switch-throwing solenoids 3 or 4 by reason of the current remaining thereon unduly long. The current which is used in these switch-throwing magnets is a relatively heavy current suitable for doing the heavy work of throwing the switch 2 and it would be detrimental to the solenoids 3 and 4 if this heavy current remained on them unduly long. The timing mechanism prevents this and ensures that the circuit of the switch-throwing magnet will be opened after the magnet has done its work even though the timing relay 6 remains energized, as might occur if the trolley car should stop with the trolley wheel in engagement with the contact strips 9. Furthermore the timing mechanism will function to ensure the closing of the circuit of the switch-throwing magnet and then to open the circuit after a predetermined length of time even though the timing relay 6 is energized for a very short period of time which of itself would be insufficient to enable the switch-throwing solenoids to accomplish their function. If the timing relay 6 is energized for even a very brief period it will operate to attract its armature and thereby close the circuit of the switch-throwing magnet at the contacts 33, 34 and even if the timing relay 6 should be immediately de-energized as soon as the circuit of the switch-throwing magnet is closed yet the timing mechanism will maintain the switch closed for the required predetermined length of time. By reason of this it is possible to use a relatively short contactor 8 which is only long enough to ensure that the timing relay 6 will be energized. The use of a short contactor is advantageous because it reduces the weight which is supported by the trolley wire.

I have heretofore referred to the relay 17 as the selective relay which functions to select which of the two switch-throwing magnets 3 or 4 shall be operated. The operation of this selective relay is controlled by the motorman of the car and he renders it operative or non-operative by keeping the current on the motor of the car or shutting it off as the trolley wheel engages the contactor 8.

It will be noted that the winding of the selective relay 17 is in the portion of the relay circuit between the point where the wire 12 taps the trolley wire 1 at 13 and the contactor 8. If the current is shut off from the car motor during the time that the trolley wheel is in engagement with the contactor 8 then the only current which will flow through the wire connections 12, 16 and the selective relay 17 is the current which passes through the timing relay 6 and such current as is used for the lights and heaters of the car. The selective relay 17

is so wound that this current of itself will not attract the armature 40 and hence if the current is shut off from the car motor while the trolley is in engagement with the contactor the selective relay 17 will be non-operative and its armature will remain in contact with the contact 41 thus placing the switch-throwing solenoid 4 in the circuit. If, however, the controller of the trolley car is positioned so as to keep the current on the car motor when the trolley wheel passes the contactor 8 then since the contactor separates the trolley wheel from the trolley wire the current for the car motor will be taken from the trolley wire through wire connections 12, 16 and the selective relay 17 and thence through the wire connections 18 and 20 to the contactor and from the contactor to the trolley wheel and thence to the motor. At the same time the bridging of the contact strips 9 will allow current to flow through the timing relay 6 so that when the current is on the car motor the selective relay 17 has passing therethrough not only the current necessary to operate the timing relay 6 and the lights and heater of the car but also the current taken by the motor of the car. This selective relay is so wound that this heavier current is sufficient to raise the armature 40 against the contact 43 and thus close the branch circuit 44 through the switch-throwing solenoid 3.

Therefore, if the motorman wishes to actuate the switch point 2 by the solenoid 4 he will shut the current off from the motor while passing the contactor 8 thus causing the selective relay 17 to remain inactive so that the current will be sent through the branch 42 of the switch-throwing solenoid 4. On the other hand if he wishes to actuate the switch by the switch-throwing solenoid 3 he will leave the current on the motor while passing the contactor 8 and this will render the selective relay 17 operative to close the branch circuit 44 through said switch-throwing solenoid 3. With this arrangement, therefore, the motorman will leave the current on the motor or shut it off from the motor when passing the contactor 8 depending on which way he wishes the switch point 2 to direct the car.

I have also provided herein means whereby after the timing relay 6 has operated to close the circuit through the switch-throwing solenoid, said relay will be held inoperative for further action until after the car which actuated it has passed the switch point. The purpose of this is to provide means which will prevent a second car which is closely following a first car from throwing the switch point until after the first car has passed the switch. Otherwise, it might be possible for the second car to follow the first car so closely that said sec-

ond car would throw the switch before the rear wheels of the first car had passed the latter.

This end is accomplished by providing 5 means whereby when the relay 6 is energized by a car engaging the contactor 8 said relay will remain energized until after the car has passed the switch point 2.

The armature 29 of the timing relay is 10 provided with an extension 57 which carries an insulated bridging contact adapted to bridge two contacts 58, 59, the contact 59 being connected by a wire connection 60 to the wire connection 24 on the input side 15 of the timing relay 6 and the contact 58 being connected by a wire connection 61 to a contact 62 which is normally engaged by a contact 63 carried by a contactor member 64 that is pivoted at 65 to a frame 67 that 20 is supported by two posts 66 rising from the trolley wire 1. This frame 67 is forked at one end and a cross bar 68 of wood or other insulating material is supported by said forked end. The contact 62 is carried by 25 this cross bar 68 so that said contact is insulated from the trolley wire. The contactor 64 is arranged to be engaged by the trolley wheel of a passing car and when so engaged the trolley wheel will raise it and thereby 30 separate the contacts 62, 63.

The member 64 is electrically connected to the trolley wire 1 so that when the contacts 62, 63 are closed and the bridging contact 57 closes the contacts 58, 59 a current will 35 be established through the timing relay 6 from the trolley wire through the member 64, contacts 63, 62, circuit wire 61, contacts 58, 59 wire connection 60, thence to the timing relay 6, wire connection 26, resistance 40 28 to the ground 27. The energizing of the relay 6 thus closes its circuit at the contacts 58, 59 and said circuit will remain closed until the car engages the contactor 64 and opens the circuit at the contacts 62, 63. 45 This contact 64 is so situated relative to the switch point 2 that the trolley wheel will not open the circuit until after the car has passed the switch point 2.

With this construction, therefore, when 50 the relay 6 has been energized by the trolley wheel bridging the contact strips 9 said relay will remain energized thus holding its armature 29 depressed until after the car has passed the switch point 2, and has 55 opened the circuit 61 by separating the contacts 62, 63. Hence any following car cannot actuate the timing relay until the first car has safely passed the switch.

I have heretofore referred to the stick 60 relay 36 and the function of this is to ensure that in case the selective relay 17 is made operative to raise the armature 40, said armature will be held raised until the switch-throwing magnet has completed its 65 function, even though the trolley wheel

should have meanwhile passed off from the contactor 8, which may be relatively short.

It will be noted that the current passing through the stick relay 36 is that which passes through the switch-throwing solenoid. 70 If the selective relay 17 has been rendered operative to raise the armature 40 by reason of the fact that the motorman has left the current on the car motor while passing the contactor 8 as above described, it will be 75 observed that as soon as the trolley wheel passes off from the contactor 8 the heavy current going to the car motor will be withdrawn from the selective relay 17, and the latter will thus become inoperative to hold 80 the armature 40 raised, so that unless something were provided to hold the armature 40 raised it might transpire that the current would be cut off from the switch-throwing magnet 3 before the latter had completed 85 its switch-throwing function. This is prevented, however, by the stick relay 36 because as soon as the circuit of the switch-throwing magnet is closed a current will be carried through the stick relay 36 and while this current is insufficient to raise the armature 40 yet it is sufficient to hold the armature 40 in its raised position even though the motor-operating current is shut off. Hence the circuit for the switch-throwing 90 magnet will remain closed through the switch-throwing solenoid 3 until the circuit is opened at the contacts 33, 34 by the timing relay.

I claim.

1. In an electrically-controlled track switch, the combination with a switch-throwing solenoid, of a normally-open circuit therefor, a timing relay, means to energize said relay by a passing car, and timing means operated by said relay to close the circuit of the switch-throwing solenoid and to maintain said circuit closed for a predetermined length of time regardless of the length of time during which the timing relay is energized.

2. In a device of the class described, the combination with a switch-throwing solenoid, of a normally-open circuit therefor, electro-controlled timing means rendered operative by a passing car, and operating to close the circuit of the switch-throwing solenoid and maintain the same closed for a predetermined length of time and then to open said circuit at the termination of said predetermined length of time regardless of whether the timing relay is still energized or not.

3. In a device of the class described, the combination with a switch-throwing solenoid, of a normally-open circuit therefor, a timing relay, means to energize the relay by a passing car, means to close the circuit of the track-throwing solenoid when the relay is energized and an inertia device to 125 130

open said circuit after a predetermined length of time.

4. In a device of the class described, the combination with a switch-throwing solenoid, of a normally-open circuit therefor, a timing relay, means to energize the relay by a passing car, means to close the circuit of the track-throwing solenoid when the relay is energized and an inertia device to open said circuit after a predetermined length of time regardless of whether the relay is energized or not.

5. In a device of the class described, the combination with a switch-throwing solenoid, of a normally-open circuit therefor, a contact for closing the circuit, a timing relay, means rendered operative by energizing the relay to move the contact into position to close said circuit, and a mechanical timing device for opening the circuit again after a predetermined time without regard to whether the timing relay is still energized or not.

6. In a device of the class described, the combination with a switch-throwing solenoid, of a normally-open circuit therefor, a contact for closing the circuit, a timing relay, means rendered operative by energizing the relay to move the contact into position to close said circuit, and an inertia device to open the circuit again after a predetermined length of time.

7. In a device of the class described, the combination with a switch-throwing magnet, of a normally-open circuit therefor, a timing mechanism for closing said circuit and maintaining it closed for a predetermined length of time, said mechanism comprising a magnet, means to energize it by a passing car, a contact by which the circuit is closed, an armature for the magnet, means normally connecting the armature and contact whereby when the magnet is energized the contact is actuated to close the circuit of the switch-throwing magnet, and an inertia device for operating the contact to open said circuit after a predetermined length of time.

8. In a device of the class described, the combination with a switch-throwing magnet, of a normally-open circuit therefor, a timing mechanism for closing said circuit and maintaining it closed for a predetermined length of time, said mechanism comprising a magnet, means to energize it by a passing car, a contact by which the circuit is closed, an armature for the magnet, a latch normally connecting the armature and contact whereby the contact is closed when the armature is attracted, and mechanical means for opening the contact after a predetermined length of time.

9. In a device of the class described, the combination with a switch-throwing magnet, of a normally-open circuit therefor, a

timing mechanism for closing said circuit and maintaining it closed for a predetermined length of time, said mechanism comprising a magnet, means to energize it by a passing car, a contact by which the circuit is closed, an armature for the magnet, a latch normally connecting the armature and contact whereby the contact is closed when the armature is attracted, means for unlatching the armature from the contact when the latter is closed and for opening the contact after a predetermined length of time.

10. In a device of the class described, the combination with a switch-throwing magnet, of a normally-open circuit therefor, a timing mechanism for closing said circuit and maintaining it closed for a predetermined length of time, said mechanism comprising a magnet, means to energize it by a passing car, a contact by which the circuit is closed, an armature for the magnet, a latch normally connecting the armature and contact whereby the contact is closed when the armature is attracted, means for unlatching the armature from the contact when the latter is closed, and an inertia device to open the contact after a predetermined length of time.

11. In a device of the class described, the combination with a track switch, of a solenoid for operating the same, a normally-open circuit therefor, a timing relay for closing said circuit, means to energize the relay by a car approaching the track switch and to maintain the relay energized until the car has passed said track switch, and means to open the circuit of the switch-operating solenoid at a predetermined interval after it has been closed.

12. In a device of the class described, the combination with a track switch, of a solenoid for operating the same, a normally-open circuit therefor, a timing relay for closing said circuit, means to energize the relay by a car approaching the track switch and to maintain the relay energized until the car has passed said track switch, and an inertia device to open the circuit of the switch-operating solenoid at a predetermined time after it has been closed.

13. In a device of the class described, the combination with a track switch, of a solenoid for operating the same, a normally-open circuit for the solenoid, a timing relay for closing said circuit, means to energize the relay by a car approaching the track switch and to maintain said relay energized until the car has passed the track switch, and a timing device set in operation by the closing of the solenoid circuit and operating to open said circuit at a predetermined time interval after it has been closed.

14. In a device of the class described, the combination with a track switch, of a solenoid for operating the same, a normally-open circuit for the solenoid, a timing relay

for closing said circuit, means to energize the relay by a car approaching the track switch and to maintain said relay energized until the car has passed the track 5 switch, and an inertia device set in motion by the closing of the solenoid circuit and operating to open said circuit after a predetermined length of time.

15. In a device of the class described, the 10 combination with a track switch, of a solenoid for operating the same, a normally-open circuit therefor, a timing relay for closing the circuit, a circuit through which said relay is energized, means to close the 15 circuit by a car approaching the switch and to open the circuit of the switch-operating solenoid after it has been closed for a predetermined time interval and independently of the opening of the relay circuit.

20. 16. In a device of the class described, the combination with a trolley wire, of two separate contact strips associated therewith and arranged to be engaged by the flanges of a 25 passing trolley wheel, said strips being so located that as the trolley wheel passes over them said wheel is separated from the trolley wire, a switch-throwing solenoid having a normally-open circuit, a relay for closing said circuit, a circuit for the relay including 30 the contact strips, whereby when a trolley wheel engages said contact strips the relay will be energized, and inertia means for opening the circuit of the switch-throwing magnet after a predetermined time interval.

35. 17. In a device of the class described, the combination with two switch-throwing magnets and normally-open circuits therefor, of a timing relay for closing said circuits, means to energize said relay by a passing 40 car, inertia means to open the circuit of the switch-throwing magnet after a predetermined time interval, and a selective magnet for selecting which of the two switch-throwing magnets shall be rendered operative.

45. 18. In a device of the class described, the combination with a trolley wire, of two switch-throwing magnets, and normally-open circuits therefor, a timing relay for closing said circuits, a contactor associated 50 with the trolley wire, means rendered operative by a trolley wheel engaging the contactor to energize the timing relay, a selective relay for selecting which of the two switch-throwing magnets shall be rendered 55 operative by the actuation of the timing relay, and inertia means to open the circuit of the switch-throwing magnet after a predetermined time interval.

60. 19. In a device of the class described, the combination with a trolley wire, of two switch-throwing solenoids, a normally-open circuit having a branch leading to each solenoid, a selective relay normally closing one branch, a contactor associated with the trolley wire, a timing relay for closing the cir- 65

cuit of the switch-throwing solenoids, a circuit for the timing relay which is closed by a trolley car engaging the contactor, said selective relay being in said circuit between the timing relay and the source of electrical 70 energy and an inertia device to open the circuit of the switch-throwing solenoid after a predetermined time interval.

20. In a device of the class described, the combination with a trolley wire, of two contactor strips associated therewith but insulated therefrom, and situated to be engaged by the flanges of a passing trolley wheel and to separate the trolley wheel from the trolley wire, a circuit connection from one contact strip to the trolley wire, a circuit connection from the other contact strip to the ground, a switch-throwing solenoid having a normally-open circuit, a relay for closing 75 said circuit located in the circuit connection leading to the ground and an inertia timing device to open said circuit after a predetermined time interval.

21. In a device of the class described, the combination with a trolley wire, of two contact strips associated therewith but insulated therefrom, and situated to be engaged by the flanges of a passing trolley wheel and to separate the trolley wheel from the trolley wire, a circuit connection from one contact strip to the trolley wire, a circuit connection from the other contact strip to the ground, a switch-throwing magnet having a normally-open circuit, a timing relay for 80 closing said circuit located in the circuit connection leading to the ground whereby the timing relay is energized when a trolley wheel engages the contact strips, and means associated with said timing relay to open the circuit of the switch-throwing magnet 85 after a predetermined time interval independently of the opening of the circuit of the timing relay.

22. In a device of the class described, the combination with a trolley wire, of two contact strips associated therewith but insulated therefrom and situated to be engaged by the flanges of a passing wheel and to separate the trolley wheel from the trolley wire, two switch-throwing magnets, a 115 normally-open circuit therefor, a relay for closing said circuit, a circuit connection between one contact strip and the trolley wire, a circuit connection between the other contact strip and the ground, the latter circuit connection including the relay, a selective relay in the first-named circuit connection and operative to select which of the two switch-throwing magnets shall be rendered operative and an inertia device to 120 open the circuit of the switch-throwing magnet after a predetermined time interval.

23. In a device of the class described, the combination with a track switch, of a switch-throwing solenoid, a circuit for the solenoid 130

- normally open in two places, means rendered operative by a car approaching the switch to close the circuit at one place and to maintain said circuit closed for a predetermined length of time and then to open it, a selective relay for determining which of the two switch-throwing solenoids shall be operative, means to energize said relay by a car approaching the switch, and a stick coil in the circuit of the switch-throwing magnet for maintaining the selective relay operative so long as said circuit is closed. 20
- 5 24. In a device of the class described, the combination with a track switch, of two switch-throwing solenoids, a normally-open circuit therefor, of a timing relay for closing said circuit and maintaining it closed for a predetermined length of time, a selective relay for determining which of the two switch-throwing solenoids is to be connected in said circuit, and a stick coil in 15 said circuit for maintaining the selective relay operative so long as the circuit of the switch-throwing solenoid is closed. 25
25. In a device of the class described, the combination with a track switch, of two switch-throwing solenoids and a normally-open circuit therefor, timing means rendered operative by a car approaching said switch to close said circuit and maintain it closed

for a predetermined length of time and then to open it, a selective relay for determining which of the two switch-throwing solenoids shall be operative, means to energize said relay by a car approaching the switch, and a stick coil in the circuit of the switch-throwing magnet for maintaining the selective relay operative so long as said circuit is closed. 30

35 26. In a device of the class described, the combination with a track switch, of two switch-throwing solenoids therefor, a normally-open circuit for the solenoids, a timing relay for closing said circuit, a normally-open circuit for the timing relay which is closed momentarily by a car approaching the switch thereby to render the timing relay operative, a selective relay in the circuit for the timing relay and adapted to determine which of the two switch-throwing solenoids will be operative, and a stick coil in the circuit of the switch-throwing solenoid for maintaining the selective relay operative so long as said circuit is closed. 40

45

50 In testimony whereof, I have signed my name to this specification. 55

ROY V. COLLINS.
